[57] ABSTRACT

A cantilever sewing machine table employing an overhanging top arranged to support a sewing machine outside the periphery of the top in easily accessible position while leaving the table top completely unobstructed for laying out work and providing drophead support for the machine so that it may be lowered and laterally moved into the outline of the support to a concealed position under the table top when not in use.

FIG-5

CANTILEVER SEWING MACHINE TABLE

BACKGROUND OF THE INVENTION

This invention relates to the field of furniture and more particularly to modern furniture structures for table height mounting of an operator controlled machine for use in schools, homes, manufacturing plants and the like and for storing the machine in a concealed spot within the confines of the structure. Power operated machines, such as sewing machines, clothes presses and similar power operated devices handle large quantities of material and thereby require large work tables in close association with the machines.

Heretofore, structures for supporting sewing machines and the like lacked the capability of using the structure as a layout table or desk, whether or not the machines were out in working position.

Further, the support structures formerly used were unsightly at all times and did not include the modern lines of present day furniture when the machines were not in use.

SUMMARY OF THE INVENTION

In accordance with the invention claimed, a new and improved cantilever type modern table is provided which is adapted to supporting in operating position for use and to store within it when not in use a machine tool such as a sewing machine.

It is, therefore, one of the objects of this invention to provide a cantilever supported table top structure for mounting a sewing machine or the like in which the machine is so positioned that it is easily accessible on all sides outside of the periphery of the table top.

Another object of this invention is to provide an improved sewing machine table in which the machine is telescopically moved to and from a storage space under a cantilever supported overhanging table top to provide normal unobstructed use of the table top.

A further object of this invention is to provide a cantilever style table surface combined with a storage space and drophead sewing machine telescopic support under the table top which does not in any way interfere with the unobstructed use of the table top.

A still further object of this invention is to provide a sewing machine support structure employing a cantilever supported overhanging table top having a clean and pleasing modern appearance both with the machine in operating position and when it is stored away under the table top.

Further objects and advantages of the invention will become apparent as the following description proceeds and the features of novelty which characterize this invention will be pointed out with particularity in the claims annexed to and forming part of this specification.

BRIEF DESCRIPTION OF THE DRAWING

The present invention may be more readily described by reference to the accompanying drawing in which:

FIG. 1 is a perspective view showing the cantilever type sewing machine table incorporating the features of this invention;

FIG. 2 is a left end view of the structure shown in FIG. 1;

FIG. 3 is a right end view, partially broken away showing the machine in elevated useable position and

in dash lines the machine in storage position and in an intermediate position;

FIG. 4 is an enlarged partial perspective view of FIG. 3 showing the clamping means for lacking the machine supporting shelf to the desk top when the shelf is in operative position; and

FIG. 5 is a rear view of FIG. 1.

DESCRIPTION OF THE PREFERRED EMBODIMENT

Referring more particularly to the drawing by characters of reference, FIGS. 1 - 5 illustrate a sewing machine desk or table 9 having a pair of U-shaped vertically positioned ends or legs 10 and 11, secured to a desk top 12 at opposite ends thereof. Each of the horizontal positions 13 and 14 of legs 11 and 12 are provided with adjustable pads 15.

Partition 16 divides the space between the upstanding legs 10 and 11 into a compartment 17 and a leg space 18. The leg space 18 has a drawer 19 slide mounted underneath the desk top 12 in the usual manner.

A suitable drophead machine support member 20 carrying a sewing machine 21 is located offset to one side of the leg space 18.

Since it is desirable to provide an overhang of suitable dimensions such that an operator may use the table as a work surface when facing the desk, the drophead machine support member 20 must be so arranged that it can telescopically slide outwardly of compartment 17 far enough to clear the overhang when moved vertically to a sewing position level with top of desk top 12.

The drophead machine support member 20 comprises the lever and spring mechanism 22 (well known in the art) suitably supporting a horizontally moveable rack or platen 23. Platen 23 is pulled horizontally outwardly from its compartment storage position A shown in FIG. 3 to position B.

Slidably mounted on platen 23 is a box like support 24 for supporting sewing machine 21. Reference is made to U.S. Pat. No. 3,652,143 granted Mar. 28, 1972 to Harry Wener for a more detailed description of this structure. Support 24 is provided with a horizontal track in each of the side walls of support 24. Platen 23 has a pair of steel rails fastened to its edges one on each side of box like support 24 which fit into the horizontal track as described in U.S. Pat. No. 3,652,143.

As the platen 23 is pulled horizontally outwardly of the table 10 by grasping the side walls of support 24, the weight of sewing machine 21 on platen 23 and the friction of the rails in grooves keep the platen 23 and support 24 in their relative position shown in position B (FIG. 3).

When further pull is exerted on support 24 when in position B and the drophead machine support member 20 is lifted upwardly, support 24 will slide along the rails another predetermined distance equal to or slightly more than the table top overhang so that support 24 assumes the position C shown in FIG. 3. Suitable stops (not shown) mounted on platen 23 limited the horizontal movement of support 24 relative to platen 23.

In accordance with the invention claimed, a cantilever desk type structure is provided the U-shaped legs of which support the desk and platen supported sewing machine along only two vertical supporting leg portions

25 and 26. These leg portions arranged along the back of the desk or table 10 form the bite of the U-shaped legs 11 and 12. Thus, the disclosed structure is open at the front so that the desk top 12 may be more conveniently used from the front end by an operator as a desk whether the sewing machine 21 is in usable position or stored in its compartment.

In order to more effectively tie the platen 23 to the top 12 of desk or table 9, an L-shaped clamp 28 is fastened to the rear surface of support 24 with its leg 29 extending horizontally rearwardly therefrom. Arranged in cooperating arrangement therewith is an inverted U-shaped clamp 30. Clamp 30 is provided to outline between its legs a channel 31 within which leg 29 of clamp 28 moves when the platen 23 is moved upwardly and then rearwardly during a platen elevating operation thereby stabilizing the platen for more steady sewing machine operation.

As shown in the figures of the drawing, compartment 17 in table 9 may be provided with a door 32 which closes the compartment when the drophead machine support member 24 and the associated machine 21 are stored within it.

Although but one embodiment of the present invention has been illustrated and described it will be apparent to those skilled in the art that various changes and modifications may be made therein without departing from the spirit of the invention or from the scope of the appended claims.

What is claimed is:

1. A cantilever type sewing machine table comprising in combination:

a pair of upstanding spaced U-shaped leg members, each of said U-shaped leg members comprising a pair of legs horizontally arranged and facing in the same direction,
 one of said legs of each of said members arranged to support a table top along its length and the other of said legs of each of said members being arranged for positioning along the floor,
 an overhanging table top supported on said one of said legs of each of said members,
 a compartment suspended from said table top between said members at one end of said table top,
 a drophead machine support member supported on said table top within said compartment, said drophead machine support member comprising a platen and a sewing machine support telescopedly arranged for relative movement longitudinally of each other a predetermined amount,
 said sewing machine support moving on said platen a distance substantially equal to the overhang of said table top, and
 clamping means mounted on said platen for cooperating with a fixed part thereof mounted on the under side of said table top for securing said platen and said table top in a common horizontal plane when said drophead machine support member is in machine operative position.
